UNITED STATES PATENT OFFICE.

WILLIAM W. MANGUM, JR., OF NIXON, TENNESSEE.

WIRE-STRETCHER.

SPECIFICATION forming part of Letters Patent No. 539,587, dated May 21, 1895.

Application filed August 16, 1894. Serial No. 520,517. (No model.)

To all whom it may concern:

Be it known that I, WILLIAM W. MANGUM, Jr., a citizen of the United States, residing at Nixon, in the county of Hardin and State of Tennessee, have invented a new and useful 5 Wire-Stretcher, of which the following is a specification.

My invention relates to a device for stretching wire in the construction of fences; and 10 the objects in view are to provide a simple, inexpensive and efficient apparatus adapted, with the proper adjustment of parts, to perform its functions in connection with fences of different construction.

15 Further objects and advantages of the invention will appear in the following description, and the novel features thereof will be particularly pointed out in the appended claims.

20 In the drawings, Figure 1 is a perspective view of a wire-stretcher embodying my invention. Fig. 2 is a side view, partly in section, of the apparatus. Fig. 3 is a view of the apparatus adapted for tightening tie-wires in 25 the construction of a post-and-rail fence. Fig. 4 is a detail view of the wire-clamp. Fig. 5 is a detail view of the ratchet-bar with the head for engagement with a post.

Similar numerals of reference indicate 30 corresponding parts in all the figures of the drawings.

1 designates a ratchet-bar which fits slid- 35 ably in a frame or body-portion 2, said frame or body-portion being provided with an offset box 3, in which is fulcrumed the operating or hand-lever 4. Pivotaly connected to the short arm of this operating or hand lever is an operating pawl 5, which engages the large teeth 6 on the adjacent edge of the ratchet- 40 bar, and pivotaly mounted in a slot 7 at the opposite side of the body portion or frame is a locking pawl 8, which engages the smaller teeth 9 upon the opposite edge of said ratchet- 45 bar. The operating pawl 5 is held in contact, and therefore in operative relation with the ratchet-bar, by means of a coiled spring 10, and the locking-pawl is similarly held in operative position by means of a leaf-spring 11.

The front end of the ratchet-bar is fitted 50 with a cross-head 12, which is provided with a central opening 13, engaged with a stud 14 on the extremity of said bar, said stud being

engaged in front of the cross-bar by means of a nut 15. The cross-head is provided with terminal prongs or ears 16, which are adapted 55 to engage the post against which the device is arranged in stretching a wire or wires, as shown clearly in Fig. 1. The rear end of the ratchet-bar is shaped to form a handle 17 and is provided with a perforation 18, with which 60 it is engaged a hook 19 on the end of a brace 20. This brace preferably consists of a member 21 having a series of slots 22 and a terminal offset portion 23 provided with an opening 24, and a separate member 25 which is adapted 65 to fit in the perforation 24, and is provided with a hook 26 to engage one of the slots 22. The outer or front end of this member 25 is provided with a hook 27 to engage a post, and thus support the rear end of the apparatus. 70 It will be seen that the brace or stay is extensible and therefore may be adjusted to suit the desired inclination or length of the ratchet-bar.

Fitted upon the rear end of the body-portion or frame of the apparatus is a collar 28, held in place by means of a thumb-screw 29, and provided with lateral ears 30 having perforations 31. In these perforations are fitted the draw-rods 32 provided at their rear ends 75 with nuts 33 and at their front ends with hooks 34, the front portions of said draw-rods being arranged in the keepers 35.

In Fig. 1 I have shown the arrangement of the above described device in operative relation with a fence in the process of construction, one of the runners 36 of such fence being engaged with a wire-clamp 37 having pivotaly connected jaws 38 and 39, connected at their rear ends by means of links 40 to a short 80 chain 41. The terminal link of this short chain is engaged with the hook at the front extremity of one of the draw-rods 32.

After arranging the parts as above described, the operating or hand-lever is oscillated to move the body-portion or frame of the apparatus from the post against which the ratchet-bar bears, thus straining the runner of the fence.

In Fig. 3 I have shown the apparatus arranged for use as a wire tightener in the construction of rail fences, in which the rails are held in place by means of a tie-wire 42. The tie-wire is secured by means of a staple or

otherwise to the post near its bottom, and is extended loosely upward and secured at the upper end of the same, after which the rails are inserted between the post and the wire, 5 the latter being left sufficiently loose to provide space therefor. The brace or stay is detachable from the ratchet-bar, as also is the cross-head at the front end thereof, and connected to the hooks on the front ends of the 10 draw-rods 32 are the short chains which are attached to the extremities of a slotted plate 43. This plate is arranged over the tie-wire upon the opposite side of the post from that against which the end of the push-bar bears, 15 and the operating handle is moved to draw the body portion or frame of the apparatus backward until said tie-wire is drawn against the side of the post. A staple is then driven through the slot 34 in the plate 43 to secure 20 the wire.

From the above description it will be seen that the device is simple in construction and arrangement, and that the parts may be readily adjusted, and it is obvious that various 25 changes in the form, proportion, and the minor details of construction may be resorted to without departing from the spirit of the invention or sacrificing any of the advantages thereof.

30 Having described my invention, what I claim is—

1. The combination with a hollow body portion or frame, an operating lever, and spring actuated operating and locking pawls, of a 35 ratchet-bar slidably fitted in the body portion or frame, draw-rods connected to the body portion or frame, and means connected to said draw-rods for engaging a wire, substantially as specified.

40 2. The combination with a body portion, an operating lever, and operating and locking pawls, of a ratchet-bar fitted slidably in the body portion or frame and provided with a cross-head having spurs or ears to engage a 45 post, draw-rods connected to the body portion or frame, and means attached to said draw-rods for engaging a wire, substantially as specified.

3. The combination with a body portion or frame, a hand-lever, and operating and locking pawls, of a ratchet-bar slidably fitted in the body-portion or frame and provided at one end with a cross-head for engagement with a post, draw-rods connected to the body-portion or frame, means connected to the draw-rods for engaging a wire, and a brace or stay connected to the rear end of the ratchet-bar and comprising relatively adjustable members or sections, substantially as specified. 50

4. The combination with a body portion or frame, a hand lever, and operating and locking pawls, of a ratchet bar slidably fitted in the body-portion or frame, a collar removably fitted upon the said body portion or frame, draw-rods fitting at their rear ends in perforations in said collar and at their front ends in keepers on the body portion or frame, and means connected to the draw-rods for engaging a wire, substantially as specified. 60

5. The combination with a body portion or frame, a hand lever, and operating and locking pawls, of a ratchet bar slidably fitted in the body portion or frame, draw-rods connected to the body portion or frame, means connected to the draw-rods for engaging a 70 wire, and a brace or stay connected at one end to the rear end of the ratchet bar and comprising relatively adjustable members or sections 75 21 and 25, the former of which is provided at one end with a hook to engage a perforation in the ratchet bar and at the other end with a perforated ear 23 through which the member 25 extends, and said member 25 being provided at one end with a hook 27 to engage a post and at the other end with a hook 80 26 to engage one of a series of slots 22 formed in the member 21, substantially as specified. 85

In testimony that I claim the foregoing as my own I have hereto affixed my signature in the presence of two witnesses.

WILLIAM W. MANGUM, JR.
